UNITED STATES PATENT OFFICE

143,969

DESIGN FOR AN AIRPLANE

Robert E. Gross, Bel-Air, Calif., assignor to Lockheed Aircraft Corporation, Burbank, Calif.

Application April 9, 1945, Serial No. 118,905

Term of patent 14 years

(Cl. D71—1)

To all whom it may concern:

Be it known that I, Robert E. Gross, a citizen of the United States, residing at Bel-Air, in the county of Los Angeles and State of California, have invented a new, original, and ornamental Design for an Airplane, of which the following is a specification, reference being had to the accompanying drawings, forming a part thereof:

Figure 1 of the drawings is a perspective view of an airplane embodying the new design as it would appear from a point forward to the side and above the airplane while in flight;

as it would appear from a point rearwardly, to the side, and above the airplane while in flight;

Figure 6 is a perspective view of the airplane as it would appear from a point below, slightly ahead of, and to one side of the airplane while in flight.

I claim:

The ornamental design for an airplane, substantially as shown.

ROBERT E. GROSS.
